UNITED STATES PATENT OFFICE

2,017,395

RAIL JOINT

James K. Boyd, Wilkinsburg, and Frank F. Slick,
North Braddock, Pa.

Application April 16, 1934, Serial No. 720,896

2 Claims. (Cl. 238—206)

This invention relates to rail joints, and more particularly to those used for joining railway rails, and has for one of its objects the provision of a rail joint that is provided with definite points of contacts and intermediate spaces of contraflexure, for the purpose of transmitting and distributing the excess loads and reversing stresses due to rolling wheel loads.

A rail joint of this type is disclosed in our prior Patent No. 1,696,108, issued December 18, 1928, and has proven very successful in providing increased torsional resistance as compared to those of the prior art. In addition, it has been found to function properly without regard to the design of the rail head and fishing angle, besides being materially lighter in weight than those commonly used.

The rail joint of the present invention is of the same general type as that of our prior patent referred to, but is considerably more efficient in operation, due to the reduced amount of time it takes to install. It also provides for making rapid adjustments, but at the same time employing fewer parts.

These and further objects will be apparent after referring to the drawings, in which:

Figure 1 is a side elevation of a rail joint constructed in accordance with the invention.

Figure 2 is a sectional end elevation on the line II—II of Figure 1.

Figure 3 is an end elevation of the device of the invention, with a rail joint in section.

Figure 4 is an elevation showing the combined chair and fish-plate member of the joint after it is rolled, and prior to being finally shaped.

Figures 5 and 6 are perspectives of wedges used in conjunction with the combined chair and fish-plate member.

Referring more particularly to the drawings, the numeral 2 designates the ties of a railway, which support the usual spaced rails 3 of standard T-head type. The abutting ends of the rails 3 are joined by the combined chair and fish-plate member 4 forming a part of the present invention, and which is preferably of an integral or one-piece construction, being closely similar to the construction of our prior patent referred to.

The combined chair and fish-plate member 4 comprises a base or chair plate portion 5 which is thickened on one end, as at 6, and tapered on its other end, as at 7. The base portion 5 is provided with integral fish-plate portions 8 which extend inwardly, as at 9, so as to overlie the base flanges of the rails and then extend up-

wardly parallel with the web thereof, to form web-engaging portions 10.

The fish-plate portions 8 have their portions 9 overlying the base flanges of the rails 3 shaped to form alternate projections and depressions 12 and 14, respectively, thereby providing definite points of contact of the fish-plates 8 with the rail base flanges, and intermediate spaces of contraflexure; and producing corresponding depressions 15 and elevations 16 on the exposed spaces. 10

The fish-plate portions 8 are provided with apertures or openings 17 adjacent their lower ends at the base portion 5. These openings or apertures are in alignment on either side of the rails, and preferably form three sets, one being 15 adjacent each end of the fish-plates 8, with the other set approximately adjacent the vertical center thereof and of substantially greater width.

The apertures adjacent the end of the fish-plates are arranged so as to underlie at least a portion of one of the projections 12, and the central openings 17 wholly underlie another of these projections. A wedge 18 is mounted in each pair of the aligned apertures 17 which are adjacent the ends of the fish-plate 8 and each 25 projects therefrom, as at 19. Each of these wedges 18 is recessed, as at 20, on its extended end 19.

The adjacent ends of the rails 3 almost abut, or meet, at substantially the middle of the apertures at the center of the fish-plate portions 8, and it is therefore desirable to provide individual means for forcing the separate rails up into engagement with them. A pair of wedges 21 is provided for the aligned central apertures 17. 35 These wedges 21 are substantially narrower than the wedges 18, and are adapted to occupy the aligned central apertures in side-by-side relationship. Each of the wedges 21 is also recessed, as at 20. 40

In lieu of the usual bolts to hold the fish-plate portions 8 against the webs of the rails 3, a plurality of bolts 22 are provided and each comprises generally a threaded stud 23 having a depending extension 24 on one end thereof. The 45 depending extensions 24 are each provided with a rectangular extremity 25 which is adapted to seat in the recess 20 in one of the wedges.

In accordance with conventional practice, the fish-plate portions 8 are apertured, as at 26, and 50 likewise the webs of the rails 3, as shown at 27.

In installing the device of the invention, the various wedges are inserted in the apertures 17 in the bottoms of the fish-plate portions 8 and beneath the base flanges of the rails. A bolt 22 55

is extended through each of the apertures 26 in the fish-plate portions and through the apertures 27 in the webs of the rails, which are in alinement therewith. A nut 28 is threaded on the ends of the threaded studs 23 which are remote from their depending extensions 24, and a similar nut 29 threaded on their opposite ends. The nuts 28 are tightened to draw the wedges 18 and 21 firmly under the base flanges of the rails 3. After a satisfactory adjustment of each of the wedges is made, the nuts 29 are tightened to lock the bolts 22 against movement and also to tightly clamp the web-engaging portions 10 of the fish-plates against the sides of the webs of the rails.

The several wedges 18 and 21 serve to provide definite points of contact between the base flanges of the rails 3 and the combined chair and fish-plate 4, and cooperate with the projection 12 and depressions 14 of the fish-plate portion 8 to provide definite points of contact and intermediate spaces of contraflexure for the rails.

This serves to transmit and distribute the excess loads and reversing stresses, due to the load of the wheels of the rolling stock, to the adjoining rail bodies for secondary distribution to the ties 2.

While we have shown and described one specific embodiment of our invention, it will be understood that we do not wish to be limited exactly thereto, since various modifications may be made without departing from the scope of our invention, as defined in the following claims.

We claim:

1. A rail joint comprising, in combination, a pair of rails, a combined chair and fish-plate member connecting said rails, said combined

chair and fish-plate member comprising a base portion of laterally tapering thickness and fish-plate portions, said fish-plate portions having inwardly extending portions overlying the base flanges of said rails and upstanding web-engaging portions, said inwardly extending portions of said fish-plate portions overlying the base flanges of said rails being provided with alternate projections and depressions so as to form definite points of contact and intermediate spaces of contraflexure for the rails, a wedge adapted to cooperate with the laterally tapering thickness of the base portion of said chair for adjusting said rails vertically with respect to the fish-plate portions, a bolt adapted to extend through the rail and said fish-plate portion, nuts for locking said bolt in adjusted position, and an extension on said bolt which contacts said wedge whereby the latter is forced by the movement of said bolt.

2. A rail joint comprising, in combination, a pair of rails, a combined chair and fish-plate member connecting said rails, said combined chair and fish-plate member comprising a base portion of laterally tapering thickness and fish-plate portions, at least one bolt for clamping the fish-plate member to the webs of the ends of said pair of rails, a wedge adapted to be inserted under the base flanges of said rails and to cooperate with the base portion of laterally tapering thickness to adjust said rails vertically, said bolt having an extension which engages said wedge whereby the latter is forced by the movement of said bolt.
